UNITED STATES PATENT OFFICE.

CHRISTOPHER STRACHAN, OF SOUTH ORANGE, NEW JERSEY, AND DAVID J. IRISH, OF NEW YORK, N. Y., ASSIGNEES TO MORSE DRYDOCK & REPAIR CO., OF NEW YORK, N. Y., A CORPORATION OF NEW YORK.

ATOMIZER.

Application filed November 15, 1922. Serial No. 601,117.

To all whom it may concern:

Be it known that we, CHRISTOPHER STRACHAN and DAVID J. IRISH, citizens of the United States, residing at South Orange, 5 in the county of Essex and State of New Jersey, and at New York city, in the county of Richmond and State of New York, respectively, have invented certain new and useful Improvements in Atomizers, of which 10 the following is a specification, reference being had therein to the accompanying drawing.

This invention relates to improvements in sprayers or atomizers and more particularly 15 to oil burners used in boiler furnaces and the like, in which the oil is supplied to the burner under pressure and is atomized as it is discharged into the combustion chamber of the furnace.

20 One object of the invention is to provide a simple, efficient and comparatively inexpensive mechanical burner or atomizer of this character which has no valve or other movable parts in the burner but in which 25 the size of the preferably cone-shaped spray may be varied or regulated while maintaining proper atomization of the fuel and without changing the pressure of the fuel supplied to the burner, changing the tip or 30 otherwise changing or adjusting any part of the atomizer.

In carrying out the invention, a burner head or nozzle is employed having two or 35 more sets of different sized ports and a common discharge orifice to which all of said ports lead; and a plurality of tubes disposed one within another, are employed to supply the oil to said sets of ports, a further aim being to provide novel means 40 for holding the tubes in proper relation and for permitting easy disassembling of the burner, for instance when it is necessary to clean the same.

With the foregoing and other objects in 45 view, the invention resides in the novel subject matter hereinafter described and claimed, the description being supplemented by the accompanying drawing, in which:—

Figure 1 is a longitudinal sectional view 50 of a burner constructed in accordance with my invention, the tangential ports in the head being diagrammatically shown.

Figure 2 is an enlarged longitudinal sec-

tional view of the burner head or nozzle taken on the line 2—2 of Fig. 3. 55

Figure 3 is a vertical transverse section on line 3—3 of Fig. 1.

In illustrating my invention, we have disclosed one practical form of construction, but it is to be understood that the exact details shown and described, need not be followed in all respects, as the disclosure is for 60 illustrative purposes only.

The numeral 1 designates a hollow body which is preferably cast in somewhat the 65 form of a pipe fitting, said body being provided with an open end 2, with an internal circumferential rib 3 between its ends, and with oil inlets 4 and 5 at opposite sides of this rib, for communication with oil supply 70 pipes 6 having independent control valves 7 and 8, both of these pipes being adapted to lead to a common means for supplying oil under pressure, such as the usual pumping outfit now used in connection with mechanical oil burners. 75

An outer tube 9 is threaded or otherwise connected with the open end of the body 1 and an inner tube 10 which is spaced from the tube 9, has a frictional engagement with the inner surface of the rib 3, the front ends of these tubes being closed by a head or nozzle 11 which is by preference of the two-part construction shown. One part of this head is shown in the form of a substantially 85 flat disk 12 having a projecting flange 13 which is connected suitably with the inner tube 10, for instance by threading. The peripheral portion of the disk or closure 12 abuts the front end of the outer tube 9 and is held in this position by a cap or tip 14 which is threaded or otherwise suitably connected with said outer tube. This cap is provided with a central oil discharge orifice 15 whose rear end is enlarged as indicated 90 at 16, forming a chamber between the front and rear sides of the head 11, which chamber is preferably of the conical shape shown.

An outer series or group of ports 17 is formed through the closure disk 12 and leads from the outer tube 9 to the chamber 16, while an inner series or group of ports 18 is also formed through said disk to establish communication between the inner tube 10 and said chamber 16. One group or set 100 of ports has a greater maximum capacity 105

than the other group. In the present showing, the two sets of ports each have all of their ports of a uniform size, although the ports of one set are shown larger than those of the other set. In other words, the total cross-sectional area of the ports 17 has been shown as less than that of the ports 18. The ports of the two groups in the present showing, are tangentially disposed with respect to imaginary circles concentric with the orifice 15 in dotted lines in Fig. 2, whereby to impart a whirling motion to the oil or other fluid as it is discharged into the enlarged end or chamber 16 of the outlet orifice 15, thus causing the discharged spray to be in the form of a hollow cone.

By employing the construction shown or a substantial equivalent thereof, both the quantity of oil supplied to the furnace and the velocity of the spray may be readily controlled and the form of burner head which we have disclosed insures the most thorough atomization which is essential to the best results. It will be seen that with a constant pressure on the oil supplied through the pipes 6, a comparatively large quantity of oil may be sprayed from the burner head when both valves 7 and 8 are opened, as the oil is then supplied under pressure to both tubes 9 and 10, and is discharged through both sets of ports 17 and 18, to the chamber 16 and its orifice 15. By closing the valve 7 which supplies oil to the outer tube 9, it will be seen that all of the pressure behind the oil is exerted to force it from the inner relatively large ports 18, thereby increasing the velocity of the discharged spray, while at the same time cutting down the amount of oil sprayed from the burner. By closing the valve 8 which supplies oil to the inner tube 10 and opening the valve 7, so that the full pressure behind the oil will act to discharge oil through the ports 17, the velocity of the spray will be still further increased but the quantity of oil delivered will be reduced since the ports 17 are of less size than the ports 18.

While we have shown two independently controlled oil or fluid feeds, including the ports 17 and 18 respectively, it will be understood that a greater number may be used, if greater flexibility or range of adjustment of the burner or other atomizing device is desired.

By providing an arrangement by means of which the oil may be supplied through any one or more of two or more sets of ports, or simultaneously through all the sets, a burner is provided which may be easily regulated to meet all practical demands; and it will not be necessary to vary the oil pressure, to change the burner tip or to shut off one or more of a series of burners in a boiler furnace in order to get an effective

flame of the desired size. At the same time, we are able to get proper atomization of the oil when the burner is operating at low capacity since the oil pressure need not be lowered. The use of the control valves in the oil feed pipes obviates the necessity of valves or other movable ports in the atomizer. Attention is further directed to the fact that the construction used is simple and comparatively inexpensive regardless of the fact that it is highly efficient in operation.

We claim:

1. An oil burner comprising a burner body, and separate oil feeds leading to said body from a common source and having different maximum carrying capacities, said feeds including valve means for opening any one feed independently of the remainder or for opening all of said feeds to function simultaneously, said burner body having oil discharge means common to all of said feeds.

2. In a mechanically atomizing oil burner, a burner head having a whirl chamber and a restricted outlet orifice therefrom, separate oil feeds having oil whirling ports of different fixed sizes discharging into said whirl chamber, and cut-off valves for said feeds respectively, whereby the different feeds may be selectively or collectively thrown into play.

3. A mechanically atomizing oil burner comprising a plurality of oil feed tubes disposed one within another; a head closing one end of said tubes, said head having a single whirl chamber and a discharge orifice therefrom, oil whirling passages placing the separate oil feed tubes in communication with said whirl chamber and providing for discharging the oil at different rates of flow from the different tubes, and means for bringing any one feed tube into play or for bringing them all simultaneously into play.

4. A mechanically atomizing oil burner comprising a plurality of spaced tubes disposed one within another, a closure for the rear ends of said tubes having separate sets of ports leading from said tubes respectively, a cap mounted on the outermost tube, said cap contacting with the rear side of said closure and securing the latter in place, said cap having a single central discharge orifice formed with an enlarged inner end which communicates with all of said ports, and means whereby oil may be admitted to any or all of said tubes.

5. A mechanically atomizing oil burner comprising a hollow body having an open end, an internal circumferential rib, and oil inlets at opposite sides of said rib, an outer tube connected at one end to the open end of said body, an inner tube received within and having a frictional engagement with said rib, a closure for the rear ends of said tubes

attached to the inner tube for removal bodily therewith, said closure abutting the end of the outer tube and having ports communicating with both tubes, and a removable cap 5 on said outer tube abutting said closure and holding the latter and the inner tube in place, said cap having a discharge orifice into which said ports discharge.

6. An oil burner comprising a burner 10 head having a plurality of groups of oil inlet ports, the maximum delivery capacity of each group being different from the re-

mainder of said groups, and separate oil lines leading respectively to said groups of ports from a common source, said lines including 15 valve means for opening any one line independently of the remainder or for opening all lines to function simultaneously, said burner head having oil discharge means common to all of said groups of ports.

In testimony whereof we hereunto affix our signatures.

CHRISTOPHER STRACHAN.
DAVID J. IRISH.
